COMBINED POSTAL SCALE AND TRAY

Theodore A. Overby, Aberdeen, S. Dak.

Application September 27, 1949, Serial No. 5,183

Term of patent 14 years

(Cl. D52—10)

To all whom it may concern:

Be it known that I, Theodore A. Overby, a citizen of the United States of America, residing at Aberdeen, county of Brown, and State of South Dakota, have invented a new, original, and ornamental Design for a Combined Postal Scale and Tray, of which the following is a specification, reference being had to the accompanying drawing, forming a part thereof wherein:

Figure 1 is a perspective view of a combined postal scale and tray, showing my new design.

Figure 2 is a view in rear elevation of the combined postal scale and tray.

Figure 3 is a top plan view of the combined postal scale and tray, and

Figure 4 is a view in end elevation of the combined postal scale and tray.

I claim:

The ornamental design for a combined postal scale and tray, as shown.

THEODORE A. OVERBY.
